UNITED STATES PATENT OFFICE

ROY S. HOPKINS, OF ROCHESTER, NEW YORK, ASSIGNOR TO EASTMAN KODAK COMPANY, OF ROCHESTER, NEW YORK, A CORPORATION OF NEW YORK

PHOTOGRAPHIC RECORDING MACHINE

Application filed September 18, 1929. Serial No. 303,427.

This invention relates to photography and more particularly to photographic machines for recording documents. One object of my invention is to provide a photographic recording machine with mechanism adapted to position a document to be recorded, with mechanism for photographing the document so positioned, with a power drive for the moving mechanism and with a control member for the power drive located adjacent the path of documents being moved to the machine for causing all the parts to function. Another object of my invention is to provide a convenient release to operate the recording mechanism through a single cycle. Another object of my invention is to provide a document directing means with a trip which controls the operation of the various parts of the recording machine. Still another object of my invention is to provide a chute-like entrance to the recording machine, this chute being provided with a movable part which serves as a trip for the power operated mechanism, so that in moving a document towards the machine the trip can be readily actuated, and other objects will appear from the following specification, the novel features being particularly pointed out in the claims at the end thereof.

In my copending patent application, Serial No. 329,143, filed December 29, 1928, for document conveying and photographing machine, there is shown an entirely automatic machine for recording documents. Parts of the present machine are quite similar to parts of the machine shown in this application, and, for the general structure of the cabinet, reference may be had to this application.

Coming now to the drawings wherein like reference characters denote like parts throughout.

Fig. 1 is a fragmentary side elevation, partly in section, showing a power operated mechanism and clutch illustrating a preferred form and covering one embodiment of my present invention.

Fig. 2 is a section on line 2—2 of Fig. 1 through the clutch and associated mechanism.

Fig. 3 is a side elevation of the clutch.

Fig. 4 is an enlarged fragmentary detail

of the clutch-tripping latch in one position.

Fig. 5 is a similar view of the clutch-tripping latch in a different position from that shown in Fig. 4, and

Fig. 6 is an enlarged perspective view of 55 the clutch cam.

The mechanism shown in Fig. 1 is adapted to be enclosed in a cabinet of any desired type such as that shown in part in Fig. 1 in my copending application above referred to. Since 60 the cabinet forms no part of the present invention, it is not herein shown.

The document photographing machine consists broadly of a conveyor 1 by which documents are moved into position to be photographed by a camera 2, the documents being directed to the conveyor through a chute-like opening 3. There is a power drive including a motor 4 and a constantly rotating wheel 5 from which can be intermittently driven through the kick-out clutch 6, the camera 2 and the conveyor 1 as will be hereinafter more 70 fully described.

The conveyor, as indicated in Fig. 1, may consist of an endless belt 7 passing about a 75 pair of rollers 8 and 9, the latter roller being connected to a gear 10 meshing with a gear segment 11 which may be oscillated upon a stud 12 by means of the crank 13 which is pivotally attached at 14 to the gear segment and pivotally attached at 15 to the clutch plate 16, as best shown in Fig. 3.

In order to hold documents against the belt 7 a plurality of fine wires 17 are passed about the rollers 18 and 19. These rollers 85 may move but the wires 17 do not move, being attached to fixed parts of the machine.

Between the roller 9 and the gear 10 there is a shaft 20 upon which a one-way clutch 21 is mounted, this clutch being adapted to drive roller 9 when the gear is turned in the direction shown by the arrow and being adapted to permit the roller to remain idle when the gear segment 11 is moved in an opposite direction. Thus the conveyor is intermittently moved as the crank 13 moves a single stroke back and forth.

In order to direct documents to be photographed to the conveyor, there is a chute-like receptacle 3 having a pair of converging 100

walls 22 and 23, the former being preferably fixedly mounted on the cabinet and the latter being hinged at 24 to the fixed side walls 25 of the chute. A stop 26 is preferably arranged beneath the slanting wall 23 to limit its movement. On the lower side of the slanting wall there is a bracket 27 pivotally attached at 28 to a rod 29, this rod passing through a bearing 30 on the fixed member 31 so that it may move back and forth through this bearing.

In order to hold the hinged member 23 in the position shown in Fig. 1 a spring 32 encircles rod 29 and lies between the bearing 30 and a pair of lock nuts 33. This normally holds the parts in the position shown but slight pressure applied to member 23 moves the rod 29 against spring pressure to trip the clutch, as will be hereinafter more fully described.

The movable member 23 may either be a part of the chute or it may be a strip movably mounted in the slot, the essential feature being that there is a movable member 26 forming a clutch trip lying in or adjacent to the path of a document being passed to the machine. As will appear obvious in moving a document towards the conveyor, the fingers of the operator will naturally strike the clutch trip 23 and thus cause the various parts of the machine to function.

The mechanism of the clutch will now be described. Referring particularly to Figs. 2 and 3, the wheel 5 is constantly rotated by the motor 4 upon the sleeve shaft 34, ball bearings permitting the wheel to turn freely.

The wheel carries a clutch face 36 which may be of any frictional material, such as rubber, leather, or a suitable composition and this clutch face is preferably somewhat triangular in cross section, as shown in Fig. 2. The clutch plate 16 has a complementary annular groove 37 adapted to engage the friction material 36 when the surfaces of the groove come in contact with the friction material.

Clutch plate 16 is carried upon a shaft 38 which may move a limited distance back and forth through the sleeve shaft 34 in the following manner. Shaft 38 has an enlarged end 39 carrying a sprocket 40 and a cam plate 41, a spring 42 lies between a shoulder 43 of the sleeve shaft 34 and a shoulder 44 on a part of the support 56, this spring tending to thrust shaft 38 in the direction shown by the arrow. That is, in the direction to force the annular groove 37 into engagement with the friction material 36.

The cam plate 41 controls the position of the shaft 38 and consequently the engagement of the two clutch faces. This cam plate, as best shown in Fig. 6, comprises an annular plate 45 on which may be cut or formed a pair of cam surfaces 46 and 47. It should be noted that these two cam surfaces are not

spaced equally from the central-opening 48 of the cam plate and that they are arranged so that when rollers 48 and 49, which are carried by the rocker arm 50 arranged unsymmetrically with respect to the opening 48, bear on the plate, they will simultaneously engage the cams 46 and 47. This is best shown in Fig. 4 where both rollers 48 and 49 are shown in engagement with the cam surfaces 46 and 47.

The reason for having the rollers and cams positioned as shown in these figures is that the rocker arm 50 will have an even pressure on the disc 41 due to the fact that the two rollers engage the two cams located on both sides of the annular plate, so that there will not be a twisting action which might be caused by a single roller engaging one side of the cam plate only.

As above described this clutch is of the kick-out type. That is to say, when the clutch is tripped, the clutch plate 16 will engage the friction material 36 and the parts will turn together for one revolution, after which the clutch will automatically throw out until a second actuation of the tripping means. This is accomplished in the following manner.

Referring particularly to Figs. 2 and 3, the rollers 48 of the rocker arm 50 control the movement of the clutch through engagement with the cam disc. The rocker arm 50 is pivotally mounted upon a rounded protuberance 51 having a central aperture through which the stud 52 passes. It will be noted that the head of this stud is rounded so that for a limited movement this connection forms a type of ball and socket joint permitting a rocking movement of the arm 50. A spring 54 bearing on a washer 55 tends to hold the parts in frictional engagement. Stud 52 engages the support 56 which is attached to a relatively fixed part of the machine. The support 56 also carries a stud 57 on which is pivotally mounted a sprocket 58 carrying an eccentric arm 59. Support 56 carries still another stud 60 having a head 61 limiting the outward movement of the rocker arm 50 and spring 62 thrusts outwardly on the rocker arm in the direction shown by the arrow. On the top of support 56 there is an offset 63 carrying a stud 64 on which a latch 65 is mounted, this latch being best shown in Figs. 4 and 5. A spring 64S encircles stud 65 as best shown in Fig. 2, this spring tending to turn the latch in the direction shown by the arrows (Figs. 4 and 5) about the stud so that the operative end 66 of the latch will be normally held in engagement with the cooperating part 67 of the rocker arm.

By preventing movement of the rocker arm 50 about the pivotal support 52 in the direction shown by the arrow in Fig. 2, the wheels 48 will be retained in a fixed position and when these wheels come into engagement with the cam surfaces

46 and 47 the clutch plate 16 will be thrust from engagement with the friction material 36.

However, when the rod 29 is actuated by an operator touching the slanting member 23 in directing a document toward the conveyor, the plunger 29 will strike the end 70 of the latch member 65 and turn it against the pressure of spring 64S permitting the rocker arm 10 to move from the position shown in Fig. 4 to the position shown in Fig. 5, in which position the pressure of the wheels 49 and 50 upon the cams 46 and 47 is relieved of the shaft 38 will move in the direction shown by the arrow (Fig. 2) causing the clutch faces to come into driving engagement.

Pressure on the trip 23 having been released, the latch will return to its normal position where it will engage the rocker arm 56 20 and hold it in the position shown in Figs. 2 and 4. As shaft 38 continues to move under the impulse of the power drive, the cam surfaces 46 and 47 will again engage the wheels 48 and 49 which are now held in a fixed position by the latch, so that as the wheels ride on the cam surfaces, shaft 38 will be again thrust out of driving engagement with the clutch. It will thus be seen that the clutch trip 23 controls the power drive for the conveyor. 30 It likewise controls the power drive for the camera since the camera is operated from the eccentric 59 through a crank 80 as best shown in Fig. 1, the crank 80 being pivotally attached at 81 to a rocker 82 which operates the mechanism of the camera 2. This rocker arm causes the pulldown mechanism 83 to move a fresh area of film in the place behind the objective 84, and cause the shutter 88 to make an exposure. The details of the camera construction will not be more fully described since they form no part of the present invention.

It should be noticed that eccentric 59 is driven by the sprocket 58 through a chain 45 driven from the sprocket 40. In the present embodiment of my invention the relation of sprockets 40 and 58 is two to one. That is to say, each time sprocket 40 turns two revolutions, sprocket 58 turns a single revolution. This is because the present embodiment of my machine is so arranged that the conveyor moves two cycles for each single picture which is taken as I prefer to form the images of two documents on a single frame 55 of film. This, however, is not material to the present invention, it being only necessary that the camera mechanism and the conveyor mechanism both be controlled through a single clutch trip, so that the operation of photographing the documents consists of merely touching the clutch-releasing lever as the documents are placed into the chute through which they are guided to the conveyor.

While this machine is particularly designed for photographing checks, it is also

equally suitable for other documents of a size which can be accommodated by the mechanism.

Having thus described my invention, what I claim as new and desire to secure by Letters Patent is:

1. In a photographic recording device, the combination with movable mechanism for positioning documents, of a document conveyor, means for directing documents to said conveyor including a smooth walled chute, front side and rear walls included in the chute, the rear wall being mounted to move a limited distance with respect to the other of said walls and projecting above the front wall, a power drive, a clutch, and connections between the power drive and document conveyor through said clutch, connections between the movable chute wall and said clutch for operating the clutch, whereby movement of said movable chute wall may actuate said clutch and cause a document to be moved by the document conveyor.

2. In a photographic recording device, the combination with movable mechanism for positioning documents, of a document conveyor including a smooth walled chute, front side and rear walls included in the chute, said rear wall projecting above the front wall, at least two of which walls are inclined toward each other to form a narrow opening to direct documents to a conveyor, the rear wall being movably mounted, a stop for limiting the movement of the movably mounted wall so that said wall with said other inclined wall will form a relatively narrow opening to direct prints to said document conveyor in either of two possible positions, a power drive for the document conveyor, a control mechanism for said power drive, and connections between said control mechanism and said movable wall of said chute to operate the document conveyor.

3. In a photographic recording device, the combination with movable mechanism for positioning documents, of a document conveyor including a smooth walled chute, said chute including a front wall, a rear wall higher than said front wall, side walls closing the ends of the front and rear walls, the rear wall being movably mounted with respect to the other walls, a power drive for the conveyor including a continuously rotating member, a second member adapted to be engaged by and rotated with the rotating member, a clutch for driving the second member from the rotating member, and a clutch actuating mechanism operably connected to the movable chute wall whereby movement of the wall may actuate the clutch for driving the conveyor from the continuously rotating member.

4. In a photographic recording device, the

combination with movable mechanism for positioning documents, of an endless belt conveyor for moving the documents, a chute for directing documents toward said conveyor, said chute comprising front and back walls which converge toward a narrow opening, said back wall being higher than the front wall, side walls which substantially close the openings at the ends of the front and back walls, the back chute wall being hingedly mounted and adapted when swung about its hinge to vary the size of the opening between the walls, a constantly rotated power drive, a driven element connected to the endless belt, a clutch for moving the endless belt from the constantly rotated power drive, a clutch trip member operably connected to the hinged chute wall whereby movement of said wall may actuate the clutch and drive the document conveyor.

Signed at Rochester, New York, this 13th day of September, 1929.

ROY S. HOPKINS.
